UNITED STATES PATENT OFFICE.

ARTHUR R. KRAUSE, OF WOODHAVEN, AND FREDERICK W. MATHIEU, OF NEW YORK, N. Y.

DESIGN FOR A LAMP SHADE OR ANALOGOUS ARTICLE OF MANUFACTURE.

Application filed December 15, 1924. Serial No. 11,705. Term of patent 7 years.

To all whom it may concern:

Be it known that we, ARTHUR R. KRAUSE, and FREDERICK W. MATHIEU, citizens of the United States of America, and residents of Woodhaven, county of Queens, and State of New York, and of the city, county, and State of New York, respectively, have invented a new, original, and ornamental Design for Lamp Shades or Analogous Articles of Manufacture, of which the following is a specification, reference being had to the accompanying drawing, forming a part hereof.

We claim:

The ornamental design for a lamp shade or analogous article of manufacture, substantially as shown and described.

ARTHUR R. KRAUSE.
FREDERICK W. MATHIEU.
